CLAMP AND CUTTER ACTUATING MECHANISM.

1,359,250.

Specification of Letters Patent. Patented Nov. 16, 1920.

Application filed September 18, 1919. Serial No. 324,505.

To all whom it may concern:

Be it known that I, HAROLD E. HOUSEMAN, a citizen of the United States, residing at Philadelphia, county of Philadelphia, and State of Pennsylvania, have invented a new and useful Improvement in Clamp and Cutter Actuating Mechanism, of which the following is a full, clear, and exact description, reference being had to the accompanying drawings, which form a part of this specification.

The object of my invention is to effect the operation of certain parts of the machine at certain precise times during its operation and particularly at certain exact transitory points in the operation of the oscillatory mechanism. One of the elements whose operation it is desired to accurately time is the clamping and cutting mechanism. While my invention comprises means for thus exactly timing the actuation of the clamp and cutter, it also, in a broader aspect comprises means whereby the time of operation of any element of the machine may be predetermined with exactitude. The reason why the conventional knitting machine is either incapable of being, or has not been, arranged to effect exact timing of certain of the elements will be developed hereinafter. Preliminarily, it may be advisable to give a general description of the operation of a knitting machine of a conventional type.

The principal parts of a knitting machine are the needle cylinder and the cam ring, the first of which is rotatable while the second is stationary (although in some machines this arrangement is reversed), means to rotate the needle cylinder, means to oscillate the needle cylinder, a driving shaft, a clutch by means of which the needle cylinder is caused to be operated by either the rotary driving means or the oscillatory driving means, and pattern mechanism controlling the shifting of the clutch.

During the knitting of the leg of the stocking and during the knitting of that part of the stocking between the heel and toe (which may be called the foot), the needle cylinder is continuously rotating and all the needles are down and in action. At the beginning of the heel or toe, the clutch is shifted to change the movement of the needle cylinder to one of oscillation, the needles extending throughout one half the circumference of the needle bed (which may

be called the rear bank of needles) are initially thrown out of action, and mechanism is operated to clamp and cut the yarn and cause the needles to take on new yarn. The movement out of action of the rear bank of needles may be effected by providing such needles with long butts and causing a cam to be moved into action to engage such needles and lift them out of action. During the oscillation of the needle cylinder, the needles of the front bank are lifted out of action, one at a time, first at one end of the semi-circumference and then at the other end, and so on alternately, until only a limited number of needles in the central part of the front bank is in action, thus knitting a flat fabric of gradually decreasing width. This intermittent raising of the needles is effected by what are known as lifting or narrowing pickers.

The inactive needles of the front bank are now moved down into action in the reverse order in which they were moved out of action. This operation may be effected by lowering or widening pickers, the lifting pickers being rendered inactive; or it may be effected by the conjoint action of the lifting pickers and lowering pickers, the lifting pickers continuing in action, and the lowering pickers operating to depress two needles at a time. In either case, the result is to knit a fabric of gradually increasing width until all the needles of the front bank are restored to action.

The clutch is now shifted to change the movement of the needle cylinder from oscillation to rotation, the yarn changing and yarn clamping and cutting mechanism is operated and the rear bank of needles, provided with long butts, are moved down into action by means of an appropriate cam.

It may also be necessary to change the yarn and operate the clamp and cutter during the knitting of the circular portion of the stocking, as during the knitting of the leg, or where it is desired to knit the lower half of the foot of double thickness. Various other operations may be required to be effected, such, for example, as changing the length of the stitches at different parts of the stocking, and, at the conclusion of the knitting operation, automatically casting off the stocking, leveling the needles and stopping the machine.

In the conventional knitting machine, the

elements for controlling most of these operations are rendered operative by means of pattern mechanism comprising a pattern chain, which is given an intermittent, but 5 regular motion, and a pattern disk, drum or cylinder, or auxiliary pattern chain, or equivalent mechanism, which is operated, indirectly, from the driving shaft, at irregular intervals dictated by lugs on the pattern chain. The pattern disk, drum, or the like, carries devices, usually cams, which 10 actuate mechanism to effect the various operations, or most of them, above described.

In the conventional knitting machine, the 15 positive movement of the pattern disk or drum is effected by a ratchet-operating pawl that is actuated by the oscillatory or reciprocatory driving means hereinbefore mentioned, although in the Harry A. Houseman 20 Patents, No. 1,206,848, December 5, 1916 and 1,207,757, December 12, 1916, the operation is effected by an eccentric cam turning constantly with the rotary driving means. In those machines wherein the pattern drum 25 or disk is operated by the oscillatory driving means, it is obvious that the pattern drum or disk must be turned during one or the other stroke of such oscillatory driving means, while in the Houseman patents 30 above named the cam is so shaped as to impart to the pattern disk a movement coincident in time with that which it would receive were it operated from the oscillatory driving means.

35 It so happens that it is desirable to shift the clutch, change the yarn and raise or lower the rear bank of needles coincidently with the stroke of the oscillatory driving means, and therefore the conventional operation of these parts by means of the 40 oscillatory driving means is not particularly objectionable. The operation of the yarn clamp and cutter, however, particularly when changing onto the heel or toe, is unsatisfactory on all types of machines. I 45 have discovered that the reason for the defective operation of clamps and cutters is due not to the defective construction of the same, but to their untimely operation, and that far better results can be secured if the 50 clamping and cutting mechanism is rendered operable when the oscillatory driving means is at its dead center when passing from circular to oscillatory work. I have 55 also discovered that it is undesirable to operate the clamp and cutter mechanism, during the knitting of the leg, when the oscillatory driving means is at its dead center, but that it is desirable to operate it just 60 before the oscillatory driving means reaches its dead center.

The reason for the defective operation of the clamp and cutter when it is operated by, or coincidently with the stroke of, the oscillatory driving means may be briefly ex-

plained as follows: The yarn, at this time, has traveled only a limited distance into the clamp and is not properly positioned relatively thereto. Hence the operation of the clamp and cutter is uncertain, and in any 70 event there is more or less accumulation of particles of yarn in the clamping and cutting mechanism due to clamping and severing the yarn while improperly positioned. If the clamp and cutter are actuated when 75 the oscillatory driving means reaches its dead center, the yarn will have traveled as far as possible into the clamp and cutter, it will be properly positioned relatively thereto, and the action of the clamp and cutter 80 will be reliable and substantially perfect. On the other hand, if the operation of the clamp and cutter, when they are brought into action during the knitting of circular fabric, is delayed until the oscillatory driving 85 means reaches its dead center, so great a length of yarn would be fed to the clamp and cutter, due to the speed at which the machine travels in rotary knitting, that, after cutting, an objectionable length of 90 yarn will remain in the goods.

It is obvious that if the operation of the clamp and cutter is dependent upon the pattern disk or drum and should take place, when going on to the heel or toe, at or about 95 the dead center of the oscillatory driving means, it cannot be so effected on any machine which actuates the pattern drum or disk from the oscillatory driving means; nor can it be so effected by any pattern disk 100 operating means which, while operated by the rotary driving means, is operated, as in the Houseman patents above specified, at the same time that the oscillatory driving means is on one or the other of its strokes. 105 I have, however, conceived the idea of not only operating the pattern disk from the rotary driving means, but of providing an actuating cam which will be so shaped that the pattern disk will receive the movement 110 required to bring into play the clamp and cutter, when passing onto the heel or toe, at or about the time that the oscillatory driving means reaches its dead center on the first stroke, thereby effecting the clamping 115 of the yarn and its cutting at or about the time that the needle cylinder is temporarily at rest. When the oscillatory mechanism has reached the dead center on its first stroke after the yarn change and the change 120 from circular work to oscillatory work, the first needle which has looped the new yarn will have moved to its extreme limit of travel and at which time it will have drawn the end of the yarn which was previously 125 between the clamp and cutter beyond the cutter, and thereby prevent snipping the ends of the new yarn just fed to the needles. Otherwise, as the snipped ends of the new 130 yarn would pile up on the top of the yarn

guide plate between the cutter and clamp, they would soon foul the clamp and prevent its clamping the yarn held out of action, and permit their being caught by the needles. This delay in the operation of the clamp and cutter will also insure the drawing of the old thread the maximum distance into the jaws of both clamp and cutter before they are closed.

10 However, in passing onto the heel and toe, it is also necessary, as above described, to shift the clutch to change from rotation to reciprocation, to raise the rear bank of needles, to change the yarn and move the lifting pickers into operation. If, as is usual, any or all of these operations are controlled by the pattern disk, and if the pattern disk is shifted, as above described, at the dead center of the oscillatory driving means, then these other operations will not occur at the desired time. To overcome this difficulty, I have so shaped the pattern disk actuating cam that, at each rotation, the pawl for pushing forward the ratchet disk 25 is given a series (two or more) of separate impulses. If two impulses, one of them occurs during the stroke of the oscillatory driving means, while the other occurs while the oscillatory driving means is at dead center. The cams or other devices on the pattern disk that control the shifting of the clutches, the raising out of action of the rear bank of needles, the actuation of the yarn carriers and the movement into active position of the lifting pickers (or such of these elements as are on the pattern disk) are rendered operative on the first impulse of the pattern disk, while the cam for actuating the clamp and cutter is brought into 40 action on the last impulse of the pattern disk. Thus, the timely operation of all these elements is insured.

The development of this conception has resulted in certain refinements which are of 45 importance, in that they have enabled me to operate any element at exactly the ideal time, whether at either dead center of the oscillatory driving means or at any time during the stroke of the oscillatory driving means. For example, while it is desirable to operate the clamp and cutter at one dead center of the oscillatory driving means, it is desirable to actuate the lowering pickers (for moving the needles into action one at a 50 time on the second half of the heel or toe knitting) at the other dead center. This is extremely desirable, because if the lowering pickers are subsequently moved into action (during the stroke of the oscillatory driving means) they will start picking from the wrong end of the needle bank, thus preventing an even finish of the heel and toe. In the ordinary knitting machine, either this condition is suffered, or else a more or less 55 complicated special mechanism is devised

(as in the Harry A. and Harold E. Houseman Patent No. 1,127,768, February 9, 1915) to insure a timely operation. In the present improvement, I provide the pattern disk operating cam with another "rise" that imparts a special impulse to the pattern disk at that dead center of the oscillatory driving means at which it is desired that the lowering picker shall operate, and cause the cam for actuating the lowering pickers to function during that impulse.

Finally, I may say that it is desirable that while the operation of the clutch shifter, the means for raising or lowering the rear bank of needles, the yarn changing mechanism, the pickers for raising the needles of the rear bank of needles one at a time, and the clamping and cutting of the yarn during circular knitting, shall all occur during the stroke of the oscillatory driving means, it is desirable that the clamping and cutting mechanism, when operated during circular knitting, shall take place nearer the end of the stroke of the oscillatory driving means than in the case of the other elements mentioned.

My invention, therefore, in its more specific aspect, involves the provision of a cam, actuated from the rotary driving means, having four successive "rises"; one 95 operative at about one dead center of the oscillatory driving means and which, through lever mechanism and a pawl, gives an initial turning movement to the pattern disk; a second "rise" operative (say) during the first half or middle of the succeeding stroke of the oscillatory driving means and which, during the same forward movement of the pawl, gives a second turning movement to the pattern disk; a third "rise" operative (say) during the second half of the 100 same stroke of the oscillatory driving means and which, during the same forward movement of the pawl, gives a third turning movement to the pattern disk; and a fourth 105 "rise" operative at about the other dead center of the oscillatory driving means and which, as the pawl completes its movement, gives a fourth and final turning movement of the pattern disk; the several "rises" of 110 the cam being separated by concentric portions, whereby four separate and distinct forward movements are imparted to the pattern disk.

It is clear that, by means of this contrivance, I can control, to a nicety, the exact time of operation of any element whose operation is effected or controlled by any cam or other device carried by, or moving in unison with, the secondary pattern mechanism, whether the same be a disk, drum, cylinder or auxiliary pattern chain; and where, in the claims, I use the expression "pattern disk" I mean to include an equivalent contrivance. It will be understood, 125

also, that, by regulating the length and angularity of any given "rise" of the cam, the speed of movement of the pattern disk may be controlled, thus causing the element 5 to be ultimately actuated to operate slowly or rapidly, as desired.

I shall now proceed to particularly describe one preferred embodiment of my invention. It will be understood that the embodiment is one which is applicable to a machine of the "Houseman" or "standard" type and that the specific mechanism in which I have embodied the invention would not be applicable, except perhaps in part, to machines of a different type without a substantial reorganization of such other machines. It is, however, within the capacity of the skilled mechanic, by suitable changes in detail, with the aid of my specific disclosure, to adapt my invention to machines of other types without reorganizing their construction and mode of operation in other respects.

In the drawings:

25 Figure 1 is a horizontal section, on the line 1—1 of Fig. 2, of a knitting machine embodying my invention.

Fig. 2 is a side view of the upper part of the machine, partly broken away.

30 Fig. 3 is a rear view of the upper part of the machine.

Fig. 4 is a horizontal section on the line 4-4 of Fig. 3.

Fig. 5 is an enlarged plan view of the clamp and cutter mechanism.

Fig. 6 is a partial view of the driving side of the machine.

Fig. 7 is a detail view of the cam for operating the pattern disk pawl.

40 On the frame *a* of the machine is the bed plate for the needle cylinder *b*, the cam ring

c and appurtenant mechanism. The needle cylinder is provided with slots within which

are the usual needles. The needles are movable up in their slots to render them inactive, as is well understood in the art. The

cam ring *c* carries cams (not shown) for lifting half the needles out of action and for

actuating the lifting pickers and the lower pickers. These cams and pickers are no longer used in the House.

shown, being fully disclosed in the Houseman patents of December 5 and 12, 1916, hereinbefore mentioned.

The needle cylinder b has secured to its lower end a driven gear d , which is driven

55 lower end a driven gear *b*, through an intermediate gear *c*, from a gear *f* on the clutch shaft as indicated in broken lines.

lines in Fig. 1. Loose on the clutch shaft are a rotary pinion g and an oscillatory pinion

60 h. A clutch v is splined on the shaft and is movable into engagement with either

is movable into engagement with either pinion g or pinion h , thereby effecting either the rotation or the oscillation of the needle cylinder.

65 The rotary pinion g is driven from a gear

i, which carries a bevel gear *j* in driven engagement with a bevel pinion *k* on the main driving shaft.

On the shaft o , carrying gears i and j , are two cams m and n which engage rollers p and r on a bell crank lever s (Figs. 3 and 4). This bell crank carries a quadrant t which engage the pinion h and imparts thereto its movement of constant oscillation. This oscillatory driving means is fully set forth in a patent issued to me December 24, 1918, No. 1,288,594. 70 75

The pattern disk x is provided with peripheral ratchet teeth engaged by a pawl y . The pawl y is operated at intervals by mechanism controlled by the pattern chain and actuated by the rotary cam, having four "rises," hereinbefore mentioned and herein-after more specifically described. 80

The pattern disk, in a machine of the 85 "Houseman" type, controls nearly all the operations of the knitting mechanism. Thus, it is provided, in its periphery, with a grooved cam-way z , which engages, and lifts and lowers, at predetermined times, an 90 arm w connected with the clutch v .

The pattern disk α also carries cams that control the actuation of the following mechanism: the cam (not shown) for lifting the rear bank of needles out of action at the beginning of the heel and toe and for lowering the rear bank of needles into action at the end of the heel and toe; the pickers (not shown) for lowering the needles of the front bank, one (or two) at a time, during the last half of the heel and toe knitting; the yarn carriers, which are operated whenever a change of yarn is made, as at the beginning and end of the heel and toe and on the leg; and the clamp and cutter, which are operated at each change of yarn. The pattern disk may also carry other cams for dictating other operations of the knitting mechanism, including the cams (not shown) for moving into action the lifting pickers, although on a "Houseman" machine, these lifting pickers are moved into operation by the clutch-carrying frame and are thus only indirectly controlled and timed by the pattern disk. These needle actuating cams and pickers are not herein shown, as they form no part of the present invention and are fully set forth in the Houseman patents of December 5 and 12, 1916, hereinbefore mentioned.

In the drawings, Fig. 1, I have shown some of the cams carried by the pattern disk, namely: two cams 11, 11, for controlling the pickers for lowering, one by one, or two at a time, the needles of the front bank; two cams 12, 12, for controlling the cam for lifting and lowering the rear bank of needles; three sets of cams 13, 13, 14, for controlling the yarn carriers (one at the beginning of the heel, one at the beginning of the toe. 13

and one on the leg); and three cams 15, 15, 16 for controlling the clamp and cutter in connection with the three yarn changes specified. The specific location of the cams 5 11, 12, 13, 14, 15, 16, and of the dips in the cam groove z are of primary importance, but are difficult to accurately illustrate except in a large working drawing. Each 10 should be so located that it will be rendered operative at a particular one of the several impulses imparted to the pattern disk x at a given forward movement of pawl y . In view of the description, hereinafter detailed, of the pattern disk operating mechanism, 15 and especially of the cam 50, the skilled mechanic will have no difficulty in accurately positioning the pattern disk cams so as to effect the objects of the invention.

The pawl y is carried on a lever 20 extending from a hub 21 turnable on a post. Hub 21 has also arms 22 and 23. Arm 23 carries a roller 24 engaging a constantly rotating cam 50 on the vertical shaft o . The cam 50, to which reference has hereinbefore been made, is shown in detail in Fig. 7 and is hereinafter more particularly described. Cam 50 moves arm 23 outwardly from the axis of shaft o , while a spring 25 (when free to act) moves arm 23 inwardly toward 25 the axis of the cam. If spring 25 were constantly free to act, each rotation of the cam 50 would reciprocate arms 23 and 22, lever 20 and pawl y ; and hence the pattern disk x would be actuated at frequent and regular 30 intervals; specifically, once for each turn of the shaft o , or once for each complete oscillation back and forth of the oscillatory driving means.

However, whenever arm 23 is moved outward by cam 50 (thus advancing the pawl y to advance pattern disk x), lever 22 engages and displaces the hooked end of one arm of a bell-crank lever 26 (see Fig. 6), the latter being immediately returned to normal position 45 by a spring 27, thereby causing the hooked end of lever 26 to drop back of lever 22 and prevent its return by spring 25. Pawl y , therefore, is not retracted to engage the next tooth of the pattern disk x until 50 lever 26 is moved to withdraw its hooked end from back of lever 22.

The withdrawal of lever 26 is effected by the pattern chain 30, which is driven as follows: On the rotary vertical shaft o is a cam 55 31 embraced by the bifurcated end of an arm 32 on a hub 33 swiveled on the same post on which hub 21 is swiveled. Hub 33 has an arm 34 that carries a pawl 35 engaging a ratchet 36. This ratchet is sleeved on the 60 outside of the bearing for the main driving shaft and carries a sprocket wheel 37. Pattern chain 30 extends around sprocket wheel 37 and is advanced thereby (say a distance of one-third of a link) at each reciprocation 5 of pawl 35.

Pattern chain 30 carries a series of lugs 38 adapted to actuate lever 26. When any lug 70 underrides the end of lever 26 adjoining the chain, it lifts lever 26 so as to disengage its hooked end from lever 22, thereby allowing spring 25 to draw arm 23 against the low face of cam 50 and retract the pawl y . Cam 50 then swings lever 23 so as to advance pawl y and ratchet pattern disk x forward a distance of one tooth. 75

Mounted on the bed plate at the rear of the knitting head is a stand 40 to which is pivoted a top frame 41 carrying yarn carriers 42, a yarn guiding plate 43, a clamp 44 and a cutter 45. The clamp and cutter 80 are spring-actuated to close and are opened by means of a lever 46 fulcrumed on the top frame and actuated by a slide vertical rod 47, the lower end of which is positioned to be actuated by one of the cams 15, 15, 16 85 on the pattern disk. This mechanism is more fully described in the said Houseman patents of December 5 and 12, 1916.

One of the vital features of the present invention is the construction or configuration of the cam 50. By reference to Fig. 7, it will be observed that, starting from the low point of the cam, it is provided with four distinct cam faces or "rises." The first is numbered 51, the second 52, the third 53 90 and the fourth 54. These "rises" are connected by concentric portions. It will therefore be understood that, necessarily, the operation of cam 50 upon arms 23 and 20 and pawl y is to impart to the pattern disk x , 100 each time the pawl y ratchets it forward one tooth, four successive impulses.

The several "rises" of the cam 50 are so positioned that the pattern disk x receives its first impulse when the oscillatory 105 driving means is about at one of its two dead centers, its second impulse toward the middle of one oscillation, its third impulse toward the end of such oscillation, and its fourth impulse at about the opposite dead center. The cams 11 controlling the pickers for successively lowering into action the needles of the front bank are so positioned on the pattern disk that they are rendered operative, at the middle of the heel or toe, 110 during the first impulse imparted to the pattern disk and when the oscillatory driving means is at or near dead center, and hence at the ideal time, as hereinbefore explained. The cams 12 controlling the cam 115 for lifting and lowering the rear bank of needles, the yarn carrier controlling cams 13, 13, 14, and the dips in the cam groove z for effecting the clutch shifting operation, are so positioned on the pattern disk that 120 they are rendered operative during the second impulse, or during one stroke of the oscillatory driving means. The cam 16 controlling the operation of the clamp and cutter at a yarn changing operation on the 125 130

leg is so positioned on the pattern disk that it is rendered operative during the third impulse, or just before the oscillatory driving means completes its stroke. The cams 15, 15 controlling the operation of the clamp and cutter at a yarn changing operation in going on to the heel and toe are so positioned on the pattern disk that they are rendered operative during the fourth impulse, 10 or at or about the other dead center position of the oscillatory driving means.

While I have been quite specific in reciting the exact time of operation of a number of elements controlling the knitting operation, and while my invention includes the operation of certain of such elements at such precise times, it will be understood that my invention has also a broader range, in that, by a mere alteration in the shape of the 20 controlling cam 50, or by a different positioning of the cams on the pattern disk or its equivalent, any element controlling the knitting operation may be rendered active at any desired instant during the knitting of a stocking and, more specifically, may be rendered active while the oscillatory driving means is at either dead center or at any point in its oscillation.

Having now fully described my invention, 30 what I claim and desire to protect by Letters Patent is:—

1. In a circular knitting machine, in combination, a needle cylinder, driving mechanism including rotary driving means and 35 oscillatory driving means, shifting mechanism for connecting the needle cylinder with the two driving means alternately, yarn cutting and clamping mechanism, and means to actuate said cutting and clamping mechanism while the oscillatory driving means is 40 at approximately its dead center.

2. In a circular knitting machine, in combination, a needle cylinder, driving mechanism including rotary driving means and 45 oscillatory driving means, shifting mechanism for connecting the needle cylinder with the two driving means alternately, yarn clamping and cutting mechanism, and means actuated by the rotary driving means 50 to actuate said clamping and cutting mechanism while the oscillatory driving means is at approximately its dead center.

3. In a circular knitting machine, in combination, a needle cylinder, driving mechanism including rotary driving means and 55 oscillatory driving means, shifting mechanism for connecting the needle cylinder with the two driving means alternately, a pattern disk, means actuated by the rotary driving 60 means to advance the pattern disk when the oscillatory driving means is about at its dead center, yarn clamping and cutting mechanism, and an element on the pattern disk controlling the operation of the clamp- 65 ing and cutting mechanism, said element

being so positioned as to be rendered operative in said advance movement of the pattern disk.

4. In a circular knitting machine, in combination, a needle cylinder, driving mechanism including rotary driving means and oscillatory driving means, shifting mechanism for connecting the needle cylinder with the two driving means alternately, a pattern disk, elements thereon controlling respectively a change of yarn and its clamping and cutting, and means to impart to the pattern disk two successive advance movements during a single oscillation of the oscillatory driving means, said elements being so positioned on the pattern disk as to be rendered operative respectively during one stroke of said oscillatory driving means and at about the dead center at the end of such stroke.

5. In a circular knitting machine, in combination, a needle cylinder, driving mechanism including rotary driving means and oscillatory driving means, shifting mechanism for connecting the needle cylinder with the two driving means alternately, a pattern disk, elements thereon controlling said shift, the lifting of half the needles, the individual needle raising operation and a change of yarn, another element thereon controlling the clamping and cutting of the 95 yarn, and means to impart to the pattern disk two successive advance movements during a single oscillation of the oscillatory driving means, the first mentioned elements being so positioned on the pattern disk as 10 to be rendered operative during one stroke of the oscillatory driving means and the last named element being so positioned as to be rendered operative at about the dead center at the end of such stroke.

6. In a circular knitting machine, in combination, a needle cylinder, driving mechanism including rotary driving means and oscillatory driving means, shifting mechanism for connecting the needle cylinder with the two driving means alternately, a pattern disk, means actuated by the rotary driving means to advance the pattern disk during a stroke of the oscillatory driving means and also at about the dead center at the end of 11 a stroke, yarn clamping and cutting mechanism, and a plurality of elements on the pattern disk each controlling the operation of the clamping and cutting mechanism, one of said elements being so positioned as to be rendered operative, during rotation of the needle cylinder, on the first named advance movement of the pattern disk and another of said elements being so positioned as to be rendered operative, at the shift from one driving means to another, on the second named advance movement of the pattern disk.

7. In a circular knitting machine, in combination, a needle cylinder, driving mecha- 1

nism including rotary driving means and oscillatory driving means, shifting mechanism for connecting the needle cylinder with the two driving means alternately, a pattern disk, elements thereon controlling a change of yarn, elements thereon controlling the clamping and cutting of the yarn, and means to impart to the pattern disk a movement rendering one of the last named elements operative during rotation and a movement rendering the other of the last named elements operative in passing from rotation to oscillation.

8. In a circular knitting machine, in combination, a needle cylinder, driving mechanism including rotary driving means and oscillatory driving means, shifting mechanism for alternately connecting the two driving means with the needle cylinder, a pattern disk, means actuated by the rotary driving means to impart to the pattern disk four separate advance movements during a given range of movement of the oscillatory driving means, one of which movements occurs at approximately one dead center of the oscillatory driving mechanism, the second and third of which occur during the stroke from one dead center to another, and the fourth of which occurs at approximately the other dead center, four elements on the pattern disk, one of which controls the needle lowering pickers, the second of which controls a change of yarn and the third and fourth of which control the clamping and cutting of the yarn, said four elements being

so positioned as to be operable in the respective four movements of the pattern disk.

9. A circular knitting machine having rotary and oscillatory driving means, shifting mechanism for alternately connecting the two driving means, a yarn feed for the machine when on oscillatory work, a second yarn feed for circular work, means for throwing the one yarn feed into action and the other out of action when changing from circular work to oscillatory work and from oscillatory to circular work, a clamp and cutter for said yarns, a pattern disk, means on the pattern disk for actuating the clamp and cutter when shifting from circular to oscillatory work, a second means on the pattern disk for actuating the clamp and cutter when shifting from oscillatory work to circular work, means for actuating the pattern disk to cause the first clamp and cutter actuating means to become effective when shifting from circular work to oscillatory work, and a second means in advance of the first means to cause the second clamp and cutter actuating means to become effective when shifting from oscillatory work to rotary work to compensate for the difference in speed between the oscillatory and rotary driving means.

In testimony of which invention, I have hereunto set my hand, at Philadelphia, Pa., on this 15th day of September, 1919.

HAROLD E. HOUSEMAN.
